(57) **CLAIM**

The ornamental design for a magnetic clip-on for sunglasses stems, as shown and described.

DESCRIPTION

FIG. 1 is an upper right front perspective view of a magnetic surfboard clip-on for sunglasses stems shown on an unclaimed pair of sunglasses, shown for environmental purposes only;

FIG. 2 is a front elevational view of a magnetic clip-on for sunglasses stems shown on an unclaimed pair of sunglasses, shown for environmental purposes only;

FIG. 3 is a right side elevational view of a magnetic clip-on for sunglasses stems shown on an unclaimed pair of sunglasses, shown for environmental purposes only, the left side is mirror image;

FIG. 4 is a rear elevational view of a magnetic clip-on for sunglasses stems shown on an unclaimed pair of sunglasses, shown for environmental purposes only;

FIG. 5 is a top plan view of a magnetic clip-on for sunglasses stems shown on an unclaimed pair of sunglasses, shown for environmental purposes only;

FIG. 6 is a bottom plan view of a magnetic clip-on for sunglasses stems shown on an unclaimed pair of sunglasses, shown for environmental purposes only;

FIG. 7 is an upper right front perspective view of a magnetic clip-on for sunglasses stems shown removed from sunglasses;

FIG. 8 is a front elevational view of a magnetic clip-on for sunglasses stems shown removed from sunglasses;

FIG. 9 is a right side elevational view of a magnetic clip-on for sunglasses stems shown removed from sunglasses;

FIG. 10 is a rear elevational view of a magnetic clip-on for sunglasses stems shown removed from sunglasses;

FIG. 11 is a left side elevational view of a magnetic clip-on for sunglasses stems shown removed from sunglasses; and, FIG. 12 is a top plan view of a magnetic clip-on for sunglasses stems shown removed from sunglasses, the bottom plan view is a mirror image thereof.

The dashed lines shown in FIGS. 1-6 depicting the sunglasses are environmental subject matter, all other dashed

(Continued)

lines are portions of the magnetic clip-on for sunglasses stems, neither of which form part of the claim.
